UNITED STATES PATENT OFFICE.

WALTER H. SERGENT, OF MIDDLETOWN, NEW YORK, ASSIGNOR TO IDEAL WRAPPING MACHINE COMPANY, A CORPORATION OF NEW YORK.

BELT FEED MECHANISM FOR WRAPPING MACHINES.

Application filed August 1, 1923. Serial No. 655,057.

This invention relates to a belt feeding mechanism for caramel wrapping machines and the manner of incorporating the same in the machine.

5 It is an object of this invention to provide a smooth belt feeding mechanism that conveys the caramels to the wrapping wheel so that they can be injected therein; the smooth surface of the belt allowing the 10 caramels to be injected without the same being distorted or jammed in any way between the injecting plunger and the wrapping wheel, consequently, a more accurate feed, with a higher rate of speed is possible.

15 Hitherto, a great deal of difficulty has resulted in the use or attempt to use such a belt feed on account of the wave or weave in the traveling belt. This objection has been overcome in the manner of supporting 20 and guiding the belt. The invention consists in the novel mechanism and combinations hereinafter described and more particularly pointed out and defined in the appended claims.

25 In the accompanying drawings which illustrate a preferred embodiment of this invention and in which similar reference numerals refer to similar features in the different views.

30 On the drawings:

Figure 1 is a top plan view of the feeding mechanism with a portion of the gear casing of the machine shown in section.

Figure 2 is a sectional view upon the line 35 2-2 of Fig. 1.

Figure 3 is a side elevational view of the feeding mechanism with a fragmentary view of machine that is adjacent thereto, and parts omitted.

40 Figure 4 is a sectional view upon the line 4-4 of Fig. 1.

As shown on the drawings:

In referring now to the drawing, the reference numeral 1 indicates the gear casing 45 of the caramel wrapping machine to which this invention is applied. A bearing pedestal 2 is secured to this casing and projects horizontally therefrom for supporting the wrapping wheel 3, the folding mechanism 50 and ejector not being illustrated, since the same involve no part of this invention. The feed belt travels adjacent the wrapping wheel 3 and the caramels with appropriate wrappers are periodically injected into the

wrapping wheel by an injector 5 which 55 slides through a suitable guide box 6.

A feed table 7 is suitably supported adjacent the wrapping wheel 3. The inner upper and lower margins of this table are rabbeted as indicated at 8 in Fig. 2, to provide 60 guideways in which the belt 4 travels and to allow the injector 5 to move over the table without interfering with the belt. Upon the far edge of the table there is secured a vertical guide strip 9 which extends from the 65 outermost end of the table 7 to a point adjacent the outer side of the wrapping wheel 3. This strip 9 forms a guide for the upper lap of the belt 4 upon which the caramels are conveyed and causes the upper lap of 70 said belt to travel in a straight line without any lateral movements.

Cooperating with the guide 9 there is another guide strip 10 secured to the top of the table and having its lower edge rabbeted 75 on the far-side. As shown in Fig. 4, the rabbeted portion overlaps the upper lap of the belt thus preventing the same from weaving in its travel.

The belt 4 is trained over a flanged pulley 80 11 secured upon a shaft 12 journaled in a suitable bearing bracket extending from the casing. A gear wheel 13 is secured upon this shaft and is driven by a gear 14 upon a shaft 15 which is geared to the main drive 85 of the machine. A guide roller 16 is supported upon the bracket 12 and its lower periphery is in the plane of the upper rabbeted portion of the table 7. At the outermost end of the feed table there is a bracket 90 17 upon which an adjustable vertical arm 18 is pivotally mounted. A flanged pulley 19 is rotatably supported upon the arm 19 with its upper periphery in the plane of the upper rabbeted portion of the table 7. A spring 95 pressed rod 20 is connected to the arm 18 and slidably extends through a bearing lug 21 upon the bracket 17. Adjustable nuts are secured upon the end of the rod 20 and abut the bearing lug 21. By properly adjusting these nuts, the arm 18 may be swung to regulate the tension of the belt 4 as is obvious. A guide flanged roller 22 (Fig. 3) is rotatably supported by a suitable bearing secured to the bottom of the table, and supports the lower lap of the belt in the lower rabbet of the table 7.

From the foregoing it will be apparent

that a novel form of belt feed has been provided in which the belt is guided against weaving and against lateral movement and in which the guides 9 and 10 not only aid in guiding the belt but also provide lateral guides for the caramels as they are conveyed on the belt.

I am aware that many changes may be made, and numerous details of construction may be varied through a wide range without departing from the principles of this invention, and I therefore do not purpose limiting the patent granted hereon, otherwise than necessitated by the prior art.

15 I claim as my invention:

1. In a caramel wrapping machine, the combination with a caramel wrapping wheel, of a feeding mechanism therefor comprising a table having upper and lower rabbeted 20 margins at one edge, a belt conveyer having

its upper and lower laps positioned in said rabbeted margins, a guide upon said table overlapping said belt and a lateral member upon the edge of the table for guiding the outer edge of said belt.

25

2. In a candy wrapping machine, the combination with the wrapping mechanism thereof, of candy feeding mechanism therefor, comprising a table, a flanged pulley supported at each end of said table, a belt trained over said pulleys, said table having upper and lower grooves, means for guiding and maintaining opposite portions of said belt in said grooves, and means for overlapping the upper lap of said belt to prevent 30 weaving thereof.

30

In testimony whereof I have hereunto subscribed my name.

WALTER H. SERGENT.
